UNITED STATES PATENT OFFICE

137,939

DESIGN FOR A COMBINATION STAPLE REMOVER AND LETTER OPENER

Fridolin Polzer, Norwalk, Conn., assignor to The E. H. Hotchkiss Company, Norwalk, Conn., a corporation of Connecticut

Application October 7, 1943, Serial No. 111,290

Term of patent 14 years

(Cl. D74—1)

To all whom it may concern:

Be it known that I, Fridolin Polzer, a citizen of the United States, residing at Norwalk, county of Fairfield, State of Connecticut, have invented a new, original, and ornamental Design for a Combination Staple Remover and Letter Opener, of which the following is a specification, reference being had to the accompanying drawing, forming part thereof.

In the drawing:

Fig. 1 is a side elevational view of a combination staple remover and letter opener, showing my new design; and

Fig. 2 is a top plan view thereof.

The dominant features of my design are shown in solid lines on the drawing.

I claim:

The ornamental design for a combination staple remover and letter opener, substantially as shown and described.

FRIDOLIN POLZER.
